United States Patent Office

Des. 182,889
Patented May 27, 1958

182,889

HINGE OR SIMILAR ARTICLE

Viles K. Fremstad, Van Nuys, Calif., assignor to Ajax Hardware Manufacturing Corp., Los Angeles, Calif., a corporation of California

Application November 19, 1956, Serial No. 43,828

Term of patent 14 years

(Cl. D10—9)

I claim:

The ornamental design for a hinge or similar article, as shown.
